WIRE TERMINAL

Rowland F. Gates, Toronto, Ontario, Canada, assignor to The Arrow-Hart & Hegeman Electric Company, Hartford, Conn., a corporation of Connecticut

Application July 2, 1940, Serial No. 343,669

1 Claim. (Cl. 173—259)

This invention relates to wire terminals for electrical devices, for example, switches, receptacles, terminal blocks, sockets, and in fact, any electrical devices to which wire conductors may be attached.

It is an object of my invention to make a simple, improved form of wire terminal which will enable an electrician to more quickly and more easily attach a conductor wire thereto. Another object is to provide a wire terminal which will enable more than one wire to be easily and quickly attached securely to the terminal. Other objects and advantages of my invention will appear as it is described in connection with the accompanying drawing.

In the drawing—

Fig. 1 is a plan view of a wire terminal with two wires connected thereto. The terminal screw head is partly broken away for clearness.

Fig. 2 is a side elevational view of the terminal shown in Fig. 1.

Referring to the drawing, the terminal comprises a metallic plate member 4 having an aperture 5 in one end to receive a screw or bolt so that the plate may be attached to an electrical device. The terminal plate 4 at its other end has a screw threaded aperture into which the shank 6 of a terminal screw is turned. The screw preferably has an enlarged head 7 beneath which wire conductors may be clamped upon the terminal plate 4 as the screw is tightened. Preferably marginal portions, such as the corners 8 and 9, or their equivalents, will be turned up from the top face of the terminal plate to provide shoulders. These shoulders are formed to afford an abutment for the conductor wires 10 and 12 on one side, while the screw shank 6 engages the conductor wires on the other sides thereof. In lieu of upturned corners, lateral lugs, extensions or the like could be formed on the plate and upturned to provide shoulders.

Heretofore, when one or more wires were to be connected with a wire terminal, the electrician would usually form a loop in the end of the wire and hook it around the terminal screw beneath the head thereof, or he might, if the shank of the screw were long enough and space permitted, bend the bared end of the conductor wire around the shank of the screw completely. This operation consumed a relatively large amount of time, considering the simplicity of the operation, and therefore, the operation was relatively expensive. Also, under certain conditions, space hardly permitted the electrician to make the necessary connections and this lack of space required the elec-

trician to take a longer time to make the connection, thereby still further increasing the cost of the job. When a considerable number of terminals had to be wired, the labor cost for wiring was considerably increased by these defects. If the wire was not looped around the screw shank there was danger that it would pull out from under the screw head. Attempts to obtain a secure fastening without looping have been made with special forms of terminals requiring insertion of the wire from the bottom. But this was not practical, for, in the majority of cases, it is practically essential that the terminal be wired from the top surface.

15 In order to overcome the foregoing disadvantages, I provide one or more apertures 14 and 15 in the terminal plate 4 adjacent to but outside of the area beneath the head 7 of the terminal screw, at a location removed from the corners 8 and 9. The provision of these apertures enables the electrician to insert the bared end of the wire conductor into the aperture from the top surface of the terminal and then to bend the shank of the conductor substantially parallel to 20 the surface of the terminal plate, and at the same time around the shank 6 of the terminal screw beneath the screw head 7 but between the screw shank and the shoulder afforded by the upturned corner. The electrician can accomplish this 25 operation with a minimum of motions, so that the time taken to wire a terminal is considerably reduced. Yet, at the same time, the conductor is held more firmly to the terminal as the binding screw is tightened, because the end of the 30 conductor is firmly held in the aperture (14, for example), while the shank of the conductor is held between the shank of the screw and the shoulder formed by the upturned corner (8). Thus, the conductor is held at three points when 35 40 the terminal screw is tightened.

This terminal construction has the additional advantage that two terminal wires can be secured in position with equal ease and with equal security due to the provision of the adjacent apertures 14 and 15. This is a distinct advantage and advance over prior terminal constructions, in which considerable difficulty was often encountered when two wires were to be secured to a single terminal. Quite often, in such prior 45 constructions one wire would tend to push the other out from under the screw head as the screw was tightened, thereby making the connection insecure, and, in some cases, permitting one of the conductors to be pulled away from the terminal when a small amount of strain was applied

thereto. This disadvantage of the prior terminal is overcome by my new construction at the same time that the cost of the wiring operation is reduced.

Although according to the embodiment of the invention as illustrated in the drawing, two wires can be attached to the terminal most efficiently in the manner shown, it will be apparent that, as an alternative, one or both wires could be looped completely around the shank of the terminal screw. Even if the shank of the wires were to be completely looped around the terminal screw, the provision of the apertures 14 and 15 makes this looping operation much more simple and easier to accomplish than in the prior constructions. And, at the same time, the wires will be held more securely.

Having now described my invention, I claim:

An electric wire and terminal combination comprising, a metallic terminal plate member 20

having a screw-threaded hole therethrough, a screw threaded into said hole and having an enlarged head, and means to facilitate the connection of a conductor wire to said terminal plate comprising an aperture formed in said plate adjacent to but outside that area of said terminal plate which lies beneath said screw head, a conductor wire with a bared end inserted from the top of the plate into said aperture and having its shank bent around the shank of the screw, said terminal plate having a peripheral portion turned up from the surface of the plate to form a shoulder against which the conductor wire lies, said shoulder being spaced from said aperture whereby said aperture and shoulder cooperate with the shank of the screw and engage the conductor at three points and hold it when the screw is tightened.
